POWER DRIVEN SHOE BUFFER

Herman J. Brickman, 210 E. 73rd St., New York, N.Y.

Filed Oct. 21, 1963, Ser. No. 77,058

Term of patent 14 years

(Cl. D9—2)

FIGURE 1 is a front perspective view of a power driven shoe buffer showing my new design,

FIG. 2 is a rear elevational view thereof,

FIG. 3 is a side elevational view thereof.

I claim:

The ornamental design for a power driven shoe buffer, substantially as shown.
